UNITED STATES PATENT OFFICE.

MARTIN PEARSON, OF LOS ANGELES, CALIFORNIA.

ROTATABLE FLOAT APPARATUS.

1,104,825.

Specification of Letters Patent. Patented July 28, 1914.

Application filed October 16, 1913. Serial No. 795,580.

To all whom it may concern:

Be it known that I, MARTIN PEARSON, a citizen of the United States of America, residing at Los Angeles, county of Los Angeles, State of California, have invented a certain new and useful Rotatable Float Apparatus; and I do hereby declare the following to be a full, clear, and exact description of the invention, such as will enable others skilled in the art to which it appertains to make and use the same.

This invention relates to rotatable float apparatus for flying machines, and it may be said to consist in the provision of the novel and advantageous features and in the novel and improved construction, arrangement and combination of parts and devices as will be apparent from the description and claims which follow hereinafter.

One object of the invention is to provide novel and improved apparatus of the class specified which is adapted to exert elevating and sustaining effects on the flying machine.

Another object of the invention is to provide a novel and improved construction for the collapsible floats and also for adjusting the floats.

Further objects of the invention are to provide novel and improved apparatus of the class specified, which is simple in construction, strong and durable, convenient to use, easy to adjust and operate, light in weight and effective in action.

Other objects and the advantages of the invention will be apparent to those skilled in the art from a consideration of the following description of the preferred form of construction of the apparatus, taken in connection with the accompanying drawings in which—

Figure 1 is a partly broken and sectional view taken on the line 1—1 of Fig. 4 and showing a flying machine having the invention applied thereto; Fig. 2 is an enlarged broken and sectional view taken on the line 2—2 of Fig. 1; Fig. 3 is a sectional view of one of the floats taken on the line 3—3 of Fig. 2; Fig. 4 is a sectional view of the flying machine taken on the line 4—4 of Fig. 1 and showing the rotatable float apparatus in plan; Fig. 5 is an enlarged broken and sectional view taken on the line 5—5 of Fig. 4; Fig. 6 is a fragmentary plan view of the float apparatus, showing one of the floats in inflated position; Fig. 7 is an enlarged broken and sectional view taken on

the line 7—7 of Fig. 6; Fig. 8 is an enlarged broken and sectional view taken on the line 8—8 of Fig. 4 and showing the lever and notched sector for adjusting the float in position; and Fig. 9 is a broken and sectional view taken on the line 9—9 of Fig. 1 and showing the braking device.

The flying machine 10 may be of any suitable or approved form—that shown being fully described in Patent No. 1074288, dated September 30, 1913—and is provided on the lower part of the frame 11 with a watertight compartment 12 for the operator and passengers. A ring 13 is rotatively mounted on the frame 11 adjacent to the compartment 12, and it has mounted thereon the collapsible floats 14 which are adapted to exert elevating and sustaining effects on the flying machine. The ring 13 is provided with inwardly projecting flanges 15 and 16 and it is held in position on the frame 11 by means of brackets 17 which are suitably affixed on the uprights 18 of the frame 11 and have thereon horizontal rollers 19 adapted to contact with the ring 13 and also have thereon vertical rollers 20 and 21 adapted to contact with the flanges 15 and 16.

The floats 14 are secured to rods 22 which preferably have the outer end portions thereof rotatably mounted in the free end portions of supporting bars 23 which are suitably secured to the ring 13; the inner end portions of the rods 22 being rotatably mounted on brackets 24 which are suitably secured to the ring 13.

As shown, the floats 14 consist of closed bags 25 of canvas or other suitable air-tight and watertight material which are secured to and adapted to fold against frames 26 when the bags are in deflated condition. The frames 26 are preferably formed semi-annular and inclined and gradually decreased in size from the upper or forward end thereof to the lower or rear end thereof, and consist of semi-circular strips 27 at the upper or forward part of the frame, and longitudinal strips 28 which are suitably secured to the strips 27 and which are connected together by semi-circular cross-strips 29 suitably secured thereto. In this instance the bags 25 are formed of strips 30 which are cut bias and sewed together so that the bags when inflated are substantially conical in shape and curve inwardly toward the lower or rear end thereof.

The ring 13 is preferably driven by either

or both of the rotary motors 31 which may be arranged opposite to each other. The stationary shafts 32 of the motors 31 have one end thereof mounted on standards 33 on the cross bar 34 and have the other end thereof mounted on brackets 35 suitably affixed on the uprights 18. The driving connections between the motors 31 and the ring 13 may consist of upright shafts 36 mounted in bearings 37 and 38 on the uprights 18; said shafts 36 having on the upper end thereof pinions 39 in mesh with bevel pinions 40 at the ends of sleeves 41 which are rotatively mounted on the stationary shafts 32, and having on the lower end thereof pinions 42 in mesh with teeth 43 on the ring 13. The sleeves 41 have feathered thereon parts 44 adapted to be moved by levers 45 to engage with parts 46 which are affixed to the rotors of the motors 31 and form clutch devices. Suitable clutch devices 47 operated by levers 48 may be provided on the shafts 36 whereby the ring 13 may be operatively connected with or disconnected from the shafts 36 at will. When the flying machine is of the form shown the direction of rotation of the floats 14 is preferably opposite to that of the screw 49 to avoid any tendency of the flying machine to whirl in flight. Suitable braking means indicated at 50 may be provided to be operated at will to bear against the ring 13 to stop rotation of the ring.

The means for inflating the bags 25 by air preferably consists of flexible tubes 51 connected between the bags and a circular pipe 52 which latter is suitably mounted on the ring 13 and when desired may be connected to the air pump 53 by passing the ends of a flexible tube—not shown—over nipples 54 and 55 on the outlet pipe 56 of the air pump and the inlet pipe 57 of the circular pipe 52. The air pump 53 may consist of the cylinder 58 which is provided with a suitable inlet valve 59 and outlet valve 60, piston 61, and piston rod 62 which is pivotally connected with the piston 61 and with crank shaft 63. A suitable clutch 64 may be mounted on the crank shaft 63 and may consist of female member 65 fast on the crank shaft, the male member 66 which has the sprocket wheel 67 fast thereon and is slidably mounted on the crank shaft, and an operating lever 68 which has one end thereof pivotally connected to a bracket 69 suitably secured to the cylinder 58 and has thereon a yoke or ring 70 loosely fitted in a groove on the male member 66. A sprocket chain 71 passes around the sprocket wheel 67 and around a sprocket wheel 72 on the rotor of one of the motors 31. The rods 22 may be rotated to adjust the floats 14 in position by means of levers 73 which are secured to the rods 22 and have thereon projections 74 adapted to fit in any

one of notches 75 in sectors 76 to hold the floats in adjusted position; the levers being adapted to be sprung away from the sectors to permit movement of the levers.

The means for deflating the bags 25 preferably consist of cords 77 which are fastened to the rear or lower part of the frames 26 and pass through eyes 78 suitably affixed on the sides of the bags which are free of the frames 26 and through eyes 79 on the semi-circular strips 27 and over sheaves 80 and past guide arms 81 to the reels 82 which latter have their shafts 83 journaled in standards 84 suitably secured to the brackets 24. The flexible tube being disconnected from the nipples 54 and 55 and the valve 86 on the intake pipe 57 being opened, the reels 82 may be turned by handles 85 on the shafts 83 to wind the cords 77 on the reels and cause the cords 77 to draw the bags 25 into and against the frames 26 whereupon the shafts 83 may be locked in position by means of pawls 87 engaging with the ratchet wheels 88 which are mounted fast on the shafts 83.

It will be seen that when the bags 25 are deflated and drawn against the frames 26 the floats may be turned to substantially horizontal position and rotated to exert elevating and sustaining effects on the flying machine.

While one form of construction embodying the invention has been particularly illustrated and described—many changes and modifications thereof will readily occur to those skilled in the art—wherefore the right is reserved to all such changes and modifications as do not depart from the spirit and scope of the invention as defined in the appended claims.

I claim:

1. The combination with a flying machine, of collapsible floats rotatively mounted thereon and consisting of frames and bags affixed to said frames, and means for holding the bags against the frames in deflated condition.

2. The combination with a flying machine, of inclined frames, collapsible bags affixed to said frames, and means on the flying machine for rotating said inclined frames.

3. The combination of a flying machine, collapsible floats consisting of inclined frames and bags affixed to said frames, means on said flying machine for adjusting the floats in position, and means on said flying machine for rotating said floats.

4. The combination of a flying machine, collapsible floats carried thereby and consisting of inclined frames and bags affixed to said frames, means for holding said bags against said frames in deflated condition, and means on said flying machine for rotating said floats.

5. The combination of a flying machine, a ring mounted rotatably thereon, collapsible

floats adjustably mounted on the ring, and means for rotating said ring.

6. The combination of a flying machine, a ring mounted rotatably thereon, collapsible floats adjustably mounted on the ring and consisting of inclined frames and bags affixed to said frames, means for holding the bags against the frames in deflated condition, and means on said flying machine for 10 rotating said ring.

7. The combination of a flying machine, collapsible floats mounted rotatably thereon and consisting of inclined substantially semi-annular frames and bags affixed to said

frames, said frames decreased in size from 15 one end to the other, means for holding the bags against the frames in deflated condition, and means on the flying machine for rotating the floats at will.

In testimony whereof I have signed my 20 name to this specification in the presence of two subscribing witnesses at Los Angeles, county of Los Angeles, State of California, this 10th day of October A. D. 1913.

MARTIN PEARSON.
